Primary Examiner — Darlington Ly*Assistant Examiner* — Jeremy Koenig(74) *Attorney, Agent, or Firm* — Renner, Otto, Boisselle & Sklar, LLP(57) **CLAIM**

The ornamental design for wheel, as shown and described.

DESCRIPTION

FIG. 1 is a top, right, front perspective view of a wheel showing our new design;

FIG. 2 is a left elevational view thereof; and,

FIG. 3 is a right elevational view thereof.

The uniform broken line showing in FIGS. 1-3 is for the purpose of illustrating portions of the wheel and forms no part of the claimed design.
